UNITED STATES PATENT OFFICE.

ERNEST R. SMITH, OF SAN FRANCISCO, CALIFORNIA.

ROTARY INDEX.

1,414,754.

Specification of Letters Patent. Patented May 2, 1922.

Application filed June 30, 1920. Serial No. 393,444.

To all whom it may concern:

Be it known that I, ERNEST R. SMITH, a citizen of the United States, residing in the city and county of San Francisco and State 5 of California, have invented a new and useful Improvement in a Rotary Index, of which the following is a specification.

My invention relates to improvements in rotary indexes wherein a plurality of radi- 10 ally extending leaves are rotatably and hingedly connected to a standard or frame and are arranged to receive and display variously sized display units containing matter to be displayed, such as maps, general in- 15 formation, advertisements or other data.

The primary object of the present invention is to provide an improved rotary index of the character described and constructed from a few parts of simple, cheap and effec- 20 tive construction.

A still further object of the invention is to provide an improved rotary index wherein the hinge portions are formed or stamped out of the sheet metal forming the leaf 25 thereby effecting a saving of material and the cost of assemblage and simultaneously adding to the strength and reducing the weight of moving parts.

A further object of the present invention 30 is to provide improved means for readily detaching any leaf independently of the other leaves of the index.

It is also an object to provide a plurality of variously sized detachable display units 35 whereby any portion of the data displayed may be removed or changed independently of the remaining data and display units.

A still further object is to provide leaves for a rotary index having means whereby 40 variously sized indices or index tabs may be readily attached and detached and positioned at different points on different leaves.

I accomplish these and other objects by means of the improved device disclosed in 45 the drawings forming a part of the present specification wherein like characters of reference are used to designate similar parts throughout the said specification and drawings, and which;

Fig. 1 is a perspective view of my im- 50 proved rotary index;

Fig. 2 is an enlarged broken detailed view disclosing the first step in forming one of the hinge lugs integral with the leaf;

Fig. 3 is a similar view disclosing the sec-

ond step in the formation of said lug and a reinforcing element for the edges of the leaf;

Fig. 4 is a similar view disclosing the completed channel formed with integral hinge 60 lugs;

Fig. 5 is an enlarged broken plan view of the index disclosing the manner in which the leaves are positioned relatively to each other;

Fig. 6 is an enlarged broken detailed view of one of the leaves disclosing the manner in which the variously sized display units are detachably mounted upon the leaves;

Fig. 7 is a vertical broken sectional view 70 through the upper portion of one of the leaves disclosing the manner in which one of the variously sized display units is detachably connected to said leaves;

Fig. 8 is an enlarged broken view, partly 75 in section, disclosing the manner in which the leaves are rotatably mounted upon the standard and detachably and hingedly connected thereto; and

Fig. 9 is an enlarged broken perspective 80 view disclosing the manner in which apertures are provided for attachment of the variously sized indices or index tabs.

Referring to the drawings the numeral 1 is used to designate a suitable base plate having a vertically disposed tabular standard or frame 2 extending upwardly therefrom, said frame 2 being provided with an annular flange 3, at an elevation, to support a suitable ball bearing 4 upon which rests a second 90 annular flange 6, having a depending annular flange 7 to prevent the entrance of dust or other debris to the ball bearings 4, secured to the lower end of a sleeve 8 rotatably mounted upon the standard 2 and having upper and lower annular flanges 11 and 9 respectively, said flanges 11 and 9 being provided with apertures 12 spaced at regular intervals adjacent the peripheries of said flanges, the purpose of which will herein- 100 after be more fully set forth.

The leaves 14 are preferably rectangular in shape and formed of a comparatively thin sheet of metal or other suitable material of light weight so that said leaves 14 may 105 be easily operated or swung upon their hinges or rotated, with the sleeve 8, around the standard 2.

In order to provide a simple, cheap, light and effective construction for the leaves 14 110

said leaves are provided with a reinforcing channel comprising a web portion 16 and a flange portion 17 formed by turning up parallel portions of the edges of the sheet of 5 which the leaf 14 is formed, thereby providing a channel edge of which the portion 16 forms the web and the portion 17 the flange or leg portion of said channel.

To provide an integrally formed hinge 10 and save the cost of assemblage and thereby provide a stronger and lighter hinge member, the web portions 16 are extended and reduced in width and then turned downwardly after the channel has been formed to 15 provide integral lugs 18 at the upper and lower inner corners of each leaf.

By means of this novel arrangement and construction a simple, cheap, light and effective hinge member is formed for hingedly 20 connecting the leaves 14 to the annular flanges 11 and 9, said lugs being inserted in the apertures 12 within the said flanges as disclosed in Fig. 8 of the drawings.

Each leaf 14 is provided with a series of 25 horizontally disposed suspending members or rods 19 as disclosed in Figs. 1, 4, 6 and 8 of the drawings.

Each leaf 14 is likewise provided adjacent 30 the free edges thereof with a series of regularly spaced apertures 21 which may be formed by struck up portions in the outer free edge or on both the outer free edge and the inner surface of the flange 17 adjacent said free edge as disclosed in Fig. 9 35 of the drawings.

Lateral extensions or lugs 22 of variously sized indices or index tabs 23 are tightly 40 inserted within the apertures 21 and at once form a means of moving the leaves and bearing data indicative of the subject matter 45 of the leaf to which it is attached. As one leaf may bear a greater number of different subjects of display matter than some of the other leaves it is obvious that by means of this novel arrangement the entire subject matter of any given leaf may be suitably 50 indexed.

Screwed or otherwise detachably mounted upon the upper end of the standard 2 and 55 above the top of the sleeve 8 rotatably mounted thereon, is a knob 24 having an annular flange 26 arranged to prevent raising and removal of the upper lugs 18 from the apertures 12 within the upper flange 11 60 secured to said sleeve 8, thereby normally preventing detachment of said leaves.

By removing the knob 24 a sufficient distance any leaf 16 may be easily and readily removed independently of the remaining 65 leaves in the index.

Detachably mounted upon the horizontal suspending members 19 are a series of variously sized display units 27 having spring clips 28 formed integral with the upper 70 edges thereof to detachably engage one of

said members 19, while the lower edges of said members or display units 27 are provided with offset portions 29 also formed integrally therewith and arranged to rest back of an adjacent suspending member 19 75 to prevent outward swinging of said display units when the leaves 14 are moved.

The lengths of the display units may be any multiple of the distance or distances between the regularly disposed horizontal 80 members 19 so that display units of various lengths may be used according to the amount of data contained thereon.

The width of said display units may be of any width within the width of the leaf 85 14 thereby providing a series of displaying surfaces for maps, advertisements or the like, which may be readily adapted to the amount of space required for such display.

The display units are formed preferably 90 of celluloid, aluminum, or any other light, flexible material to reduce the weight of the leaves 14 to a minimum.

The rear or back surfaces of the leaves 14 may be used as a whole in displaying large 95 matter, while the smaller display units may be used to display matter not requiring such large space.

In operation the operator turns the entire set or series of leaves and the sleeve 8 upon 95 the standard 2 by means of the indices or index tabs 23 until the required leaf, as indicated by its index tab 23, is attained. The leaves 14 are then opened as disclosed in Fig. 5 of the drawings, thereby rendering the 100 required leaf accessible and conspicuous.

The leaves 14 with their reinforcing webs 11 and flanges 17 provide a light, compact and effective construction easily movable, and cheaply constructed. 105

The flanges 3, 6, 9 and 11 as well as the standard 2 and sleeve 8 may be of standard pipe fittings thereby eliminating the necessity of constructing special parts.

Having thus described my invention 110 what I claim as new and desire to secure by Letters Patent is—

1. A rotary index comprising a suitable standard; an apertured element rotatably mounted upon the standard; a plurality of leaves having lugs formed integral with the upper and lower inner corners to rotatably engage the apertures in the rotatable element and likewise horizontal members; and a plurality of variously sized units adapted 120 to detachably engage and be suspended from said horizontal members, and arranged to display subject matter of said index.

2. A rotary index comprising a suitable standard; an apertured element rotatably 125 mounted upon the standard; a plurality of leaves having lugs formed integral with the upper and lower inner corners to rotatably engage the apertures in the rotatable element and likewise having horizontal mem- 130

bers; and a plurality of variously sized units adapted to detachably engage and be suspended from said horizontal members, and arranged to display subject matter of said index; and means for engaging the upper lugs of the leaves to prevent removal of the same from their apertures.

3. The combination with a rotary index having a plurality of radial leaves hingedly and rotatably connected thereto of horizontally disposed suspending members mounted on said leaves; and variously sized units adapted for detachable suspension from said horizontal members whereby any portion of

the subject matter of said index may be removed and changed.

4. The combination with a rotary index of a plurality of leaves radially and hingedly connected to said index and having struck up portions to provide apertures at regular intervals adjacent the free edges of said leaves; and variously sized index tabs arranged with said apertures whereby tabs may be attached at different positions on different leaves.

In witness whereof I hereunto set my signature.

ERNEST R. SMITH.
